TRANSFORMING APPARATUS

Richard B. Hunter, Shorewood, Wis., assignor to
 Cutler-Hammer, Inc., Milwaukee, Wis., a corporation of Delaware

Application January 23, 1939, Serial No. 252,264

11 Claims. (Cl. 175—312)

This invention relates to transforming apparatus for supplying energy from a constant voltage source to a translating circuit at variable voltage. The invention is particularly applicable to transformers provided with means for commutating a winding thereof and adapted to be connected to a three-wire constant voltage supply and to supply a three-wire load circuit or one or a plurality of two-wire load circuits with 10 a variable voltage.

An object of the invention is to provide a transformer having two winding sections arranged on a common magnetic core and having means to connect them in series.

Another object is to provide a transformer of the aforementioned type, having separate regulating means for each winding, said regulating means being so arranged that they may be operated simultaneously to provide equal output voltages for the two windings.

Another object is to provide a transformer of the aforementioned type which may be alternatively connected to different types of load systems.

Another object is to provide apparatus of the aforementioned character wherein the transformer is of the autotransformer type, whereby the voltages supplied to a plurality of load circuits will be maintained of like or equal values notwithstanding inequality of, or variations in the relative values of, the loads in said load circuits.

Another and more specific object is to provide a system of the aforementioned character which is particularly applicable to the illumination intensity control of a plurality of lamp circuits, whereby the lamps of the respective circuits are supplied with equal voltages which are jointly variable throughout a relatively wide range, for intensity control.

Other objects and advantages will hereinafter appear.

The transformer comprises a ring-shaped magnetic core on which are wound two winding sections, which are interconnected so as to act cumulatively with respect to the flux in the core. The transformer is further provided with two sets of contact brushes arranged symmetrically with respect to the windings and adapted to connect variable but like portions of both windings to a load circuit or circuits to supply a variable voltage thereto.

The accompanying drawing is illustrative of certain embodiments of the invention.

In the drawing,
 Figure 1 is a diagrammatic showing of a trans-

former embodying the invention and connected to a three-wire supply and to a three-wire load circuit, and

Fig. 2 shows a transformer connected to a three-wire supply circuit and to two separate 5 two-wire load circuits.

Referring to Fig. 1, the transformer is provided with a ring-shaped closed magnetic core 1 which preferably consists of a stack of annular laminations, but which may also be built up in any other suitable manner. The two halves of the core 1 have wound thereon, windings 2 and 3, respectively; the two windings being wound in opposite directions, so as to be symmetrical with respect to each other. The turns of the windings are insulated from each other and from the core 1, but are bared of insulation on the outer perimeter of the transformer. A pair of contact brushes 4 and 5 respectively are mounted on arms 6 and 7, respectively, and are arranged to 10 contact the bare portions of the wires at the periphery of the windings at diametrically opposed points of the two windings. The arms 6 and 7 are insulatedly fastened to opposite ends of a lever 8 which is rotatable about a pivot 9 at the center of the ring 1 and which lever 8 may be connected to suitable operating means in any desired manner.

One pair 10 and 11 of the diametrically opposed ends of the two windings are connected together to form a common point which in turn is connected to the neutral wire L^2 of a three-wire source of constant voltage; the other wires L^1 and L^3 of said source being connected to the other ends of the windings 2 and 3, respectively. Thus the windings 2 and 3 are connected in series with each other across the outer wires L^1 and L^3 of the three-wire system and induce in the core 1 fluxes which are cumulative. Concentric with the pivot 9 and mounted on the arms 6 and 7 are two erced sectors 12 and 13, respectively, and stationary brushes 14 and 15 are adapted to contact therewith as the lever 8 rotates. A three-wire load circuit has its outer wires L^{11} and L^{13} connected to the brushes 14 and 15, respectively, 45 while its neutral wire L^{12} is connected to the common point of the windings 2 and 3, and to the neutral wire L^2 . Thus as the lever 8 is rotated both sides of the load circuit are supplied with equal voltages which vary simultaneously 50 from a minimum to a maximum as the lever is rotated clockwise from the extreme counterclockwise position to the extreme clockwise position thereof.

Referring to Fig. 2, the same illustrates a trans-

former having a ring-shaped core 4 similar to the core of the transformer shown in Fig. 1. A winding 20 which is divided by a center tap 21 into two equal halves is wound on the core and is connected by its end terminals to the lines L¹ and L³, respectively, of a three-wire supply line, while the center tap 21 is connected to the center or neutral wire of said line. The two halves of the winding 20 are wound on the core in the same direction. The turns of the wires are bared of insulation on the outer perimeter of the transformer to make contact with the brushes 24 and 25, respectively, at diametrically opposite points of the transformer. A lamp circuit is connected 10 between the lines L²³, L²⁴ which are electrically connected to the line L² and to the brush 35, respectively while a second lamp circuit is connected between the lines L²¹, L²² which are electrically connected to the lines L¹ and to the brush 34, respectively. The brushes 24 and 25 are connected through the lever sections 26 and 27 (carried by but insulated from the central lever section 28) to the brushes 34 and 35, respectively. As the lever 28, upon the sections 26 and 27 of which the brushes 24 and 25 are mounted, is rotated, equal portions of the winding 20 are connected across the respective lamp circuits to provide them with equal variable voltages.

The drawing illustrates the use of the invention 30 as applied to an autotransformer, but it is obvious that a two-coil transformer having separate primary and secondary windings may be employed.

The connection of the brushes 4 and 5 and 24 35 and 25, respectively, to the load circuit may be accomplished by other means than those shown in Fig. 1 or 2, and instead of arranging said brushes to contact directly with the individual wires of the windings, separate contacts which in turn are electrically connected to different points on the windings may be provided for engagement by the brushes. It is further possible, if desired, to connect the supply wires in Fig. 1 to the brushes 4 and 5 and the load wires to the 40 winding ends 10 and 11, in which case the relationship of the line and load voltages will be reversed with respect to that aforescribed.

Other modifications will readily suggest themselves to those skilled in the art.

50 What I claim as new and desire to secure by Letters Patent is:

1. An alternating current transformer comprising, a ring-shaped magnetizable core, two symmetrical windings on said core and connected 55 and arranged cumulatively relatively to the core for connection across a three-wire supply circuit, and a pair of contact brushes movable simultaneously and adapted to connect equal variable sections of said windings across a load circuit.

60 2. An alternating current transformer comprising, a substantially closed magnetizable core, two symmetrical windings inductively related to said core and connected and arranged cumulatively relatively to said core for connection across 65 a three-wire supply circuit, a movable contact brush for each winding including means to connect a variable number of turns of each winding across a load circuit, and means to move said brushes simultaneously so as to maintain the 70 numbers of turns of both windings which are in circuit alike.

75 3. An alternating current transformer comprising, a ring-shaped magnetizable core, two windings on said core and connected and arranged cumulatively relatively to the latter, the

wires of said windings on the outer perimeter of the transformer being provided with contact surfaces, a contact carrier oscillatable about the center of said core, and two contact brushes carried by said carrier, one for each winding, and adapted to contact diametrically opposite surfaces of the respective windings as the carrier is moved, said brushes being provided with means to connect them across a load circuit.

4. An alternating current transformer comprising, 10 a ring-shaped magnetizable core, two windings on said core and connected in series across the outer wires of a three-wire supply circuit, while their common center is connected to the neutral wire of said circuit, the wires of said windings on the outer perimeter of the transformer being provided with contact surfaces, a contact carrier oscillatable about the center of said core, and two contact brushes carried by said carrier, one for each winding, and adapted to contact diametrically opposite surfaces of the respective windings as the carrier is moved, said brushes being provided with means to connect them across a load circuit.

5. An alternating current transformer comprising, 15 a ring-shaped magnetizable core, two windings on said core, said windings being provided with contact surfaces forming one group for each winding and arranged concentric with said core and corresponding to certain turns of 20 said windings in the natural order of the turns thereof, and a pair of contact brushes movable about the center of said core and adapted to connect equal variable sections of said windings across a load circuit.

6. An alternating current transformer comprising a substantially closed magnetizable core, two windings inductively related to said core, said windings being adapted to be connected in series to a three-wire single phase circuit, having a 40 neutral terminal, a contact brush for each winding, individual means to connect a translating circuit between said neutral terminal and said brush, and means to complete the circuit between said brush and a variable section of the 45 corresponding winding.

7. An alternating current transformer comprising a substantially closed magnetizable core, two windings inductively related to said core, means to connect one winding between one side 50 and the neutral terminal of a three-wire circuit and to connect the other winding between the other side and said neutral terminal, a contact brush for each winding, means to connect a load to said brushes, and means to complete a circuit between said brushes and equal variable sections of the corresponding windings respectively.

8. In an illumination control system, the combination with a lamp circuit, of a transformer comprising, a ring-shaped magnetizable core, two symmetrical windings on said core and connected and arranged cumulatively relatively to the latter for connection across a three-wire supply circuit, and a pair of contact brushes adapted to connect equal variable sections of said 65 windings across said lamp circuit.

9. In an illumination control system, the combination with a lamp circuit, of a transformer comprising, a substantially closed magnetizable core, two symmetrical windings inductively related to said core and connected and arranged cumulatively relatively to said core for connection across a three-wire supply circuit, a movable contact brush for each winding including means to connect a variable number of turns of each 75

winding to a load circuit, and means to move said brushes simultaneously so as to maintain the numbers of turns of both windings which are in circuit alike.

10. In an illumination control system, the combination with a lamp circuit, of a transformer comprising a substantially closed magnetizable core, two windings inductively related to said core, said windings being arranged to be connected in series to a three-wire, single-phase circuit, having a neutral terminal, a contact brush for each winding, means to connect said lamp circuit to said neutral terminal and said brushes, and means to complete the circuit between said brushes and variable sections of the corresponding windings.

11. In an illumination intensity control system, in combination, a plurality of groups of

electric lamps, a three-wire source of current supply, an autotransformer comprising a ring-shaped magnetizable core, two windings inductively associated with said core and electrically connected with each other and with said source of current supply in a manner to provide for cumulative action thereof relatively to said core, a pair of oscillatable contact brushes for said windings, said brushes being electrically connected with the respective groups of lamps to provide for connection of a variable number of turns of the respective windings in circuit with their associated groups of lamps, and means to effect joint oscillatory movement of said brushes, to thereby maintain of equal value the number of turns of the respective windings which are included in circuit.

RICHARD B. HUNTER.
